AUTOMATIC ALARM CLOCK

Application filed March 6, 1930. Serial No. 433,622.

This invention relates to an improvement in automatic alarm clocks and particularly to the means employed for automatically releasing the manual shut-off member there-
5 of after the same has been manually moved into its shut-off position.

The main object of this invention is to provide an automatic alarm clock with a simple, reliable and effective mechanism for holding its manually-operable alarm shut-off member in its shut-off position and automatically releasing the same for movement into its retired position without imposing a load of such character upon the time-train 15 as will impair the time-keeping properties thereof.

With the above and other objects in view, as will appear from the following, my invention consists in an automatic alarm-control mechanism having certain details of construction and combinations of parts as will be hereinafter described and particularly recited in the claims.

In the accompanying drawing:
25 Fig. 1 is a face view of an automatic alarm clock embodying my invention;

Fig. 2 is a broken view thereof in front elevation with a portion of the crystal and dial broken away to expose the movement; 30 the case-back being shown partially in section and the parts being in the positions due to them when the alarm shut-off plunger is in its alarm shut-off position;

Fig. 3 is a broken view thereof in trans- 35 verse section taken on the line 3—3 of Fig. 2;

Fig. 4 is a corresponding view, but showing the parts in the positions due to them after the time-train of the clock has automatically effected the release of the latch 40 to permit the retirement of the shut-off plunger;

Fig. 5 is a detached perspective view of the alarm shut-off latch; and

45 Fig. 6 in a corresponding view of the alarm shut-off slide.

In the embodiment of my invention herein chosen for illustration, I employ a sheet-metal pivotal latch 10 provided at its upper 50 end with a latch-nose 11, at its inner end

with a fork 12 and between its ends with a rearwardly-turned ear 13. The said ear is perforated, as shown, for the reception of a rivet-like stud 14 serving to pivotally connect the said latch to the forwardly-projecting end of a bracket 15 secured, by means of a screw 16, to the front movement-plate 17.

The latch-nose 11 is formed upon its upper face with a cam-surface 18 and is adapted to overlie the horizontal reach 19 of an alarm shut-off slide 20 mounted for vertical reciprocation upon the rear face of the front movement-plate 17 by means of a stud 21 carrying a friction-washer 22 bearing 60 against the rear face of the said slide. The said shut-off slide 20 may be of any approved construction and, as shown, is provided in its horizontal reach 19 with a keyhole-slot 23 for the reception of the grooved lower end 70 of a shut-off plunger 24 reciprocating vertically in a ring-head 25, screwed into the periphery of the clock-case 26. The said shut-off plunger 24 is provided at its upper exposed end with a ball-like finger-button 75 27 and serves to depress the shut-off slide 20 so as to engage the stop-finger 28 thereof with the teeth of a verge-wheel 29, forming a usual feature of alarm clocks.

For the purpose of lifting the shut-off 80 slide 20 and the shut-off plunger 24 from the positions in which they are shown in Fig. 4 when the latch 10 has been operated by the time-train, as will hereinafter appear, I employ a helical-spring 30 having 85 its lower end hooked over a rearwardly-extending stud 31 mounted upon the said shut-off slide 20, and its upper end hooked over a stud 32 rearwardly-projecting from the front movement-plate 17 before referred to.

The forked lower end 12 of the pivotal latch 10 straddles the inwardly-projecting hub 33 of an alarm-cam wheel 34 mounted 90 in the usual manner of alarm clocks, with capacity for rotary and reciprocating movement upon an alarm-set arbor 35 and carrying upon its forward face the usual alarm-cam 36 coacting with an alarm-cam 100

finger 37 radially-offsetting from the arbor 35, in the usual manner of alarm clocks.

The alarm-cam wheel 34 just above referred to is continuously driven in the usual manner of eight-day alarm clocks, so as to rotate once in each twenty-four hours, by the time-train from one of the dial-wheels 38 thereof acting through the intermediary of a gear-and-pinion train comprising a pinion 39, gear 40 and pinion 41.

The said alarm-cam wheel 34 is also urged forward so as to maintain the alarm-cam 36 in engagement with the alarm-cam finger 37 by a sheet-metal alarm-cam spring 42 perforated about midway of its length for the passage of the alarm-set arbor 35 and bearing against the hub 33 of the wheel 34 thereon. The spring 42 is secured at one end by a rivet 43 to the front movement-plate 17 and is provided at its opposite free end with an inwardly-turned alarm-stop finger 44 adapted to engage with a hammer-tail 45 offsetting from the integral arbor 46 of a sheet-metal verge 47 coacting in the usual manner with the verge-wheel 29 before referred to.

The verge 47 above referred to mounts a hammer-arm 48 carrying a hammer 49 at its outer end, which latter operates through a clearance-opening 50 in the case-back 51 to strike a cup-shaped bell 52 secured in the usual manner to the rear face of the said case-back in spaced relation thereto.

With the parts of the clock in the positions shown in Figs. 2 and 3, the shut-off slide 20 has been depressed by means of the shut-off plunger 24 to engage its stop-finger 28 with the verge-wheel 29 to halt the sounding of the alarm. In this depressed position of the slide the latch-nose 11 of the pivotal latch 10 is hooked over the upper face of the horizontal reach 19 of the said slide, so as to prevent the retirement of the same under the urge of the helical spring 30 and hence maintain the stop-finger 28 in engagement with the verge-wheel 29 to prevent the sounding of the alarm. The said nose 11 of the latch 10 is urged inward into the position shown in Fig. 3 by means of a sheet-metal spring 53 having its free end resting against the outer face of the said lever above the stud 14 thereof and its opposite end secured by a nut 54 to one of the pillars 55 of the movement.

Now, with the parts in the positions shown in Figs. 2 and 3, in which the alarm-train is prevented from running by the engagement of the stop-finger 28 with the verge-wheel 29, as above described, the rotation of the alarm-cam wheel 34 by the dial-wheel 38 of the time-train will cause the slope 56 of the cam 36 to crowd the alarm-wheel 34, together with its hub 33, rearward, with the effect of slowly rocking

the pivotal latch 10 in a direction to disengage its nose 11 from the horizontal reach 19 of the slide 20.

Simultaneously with the rocking of the latch 10, as above described, the alarm-cam spring 42 is flexed inward by the hub 33 to move the stop-finger 44 of the said spring into the path of the hammer-tail 45. It is to be noted that the parts are so proportioned that the stop-finger 44 is interposed in the path of the hammer-tail 45 before the latch 10 has been swung sufficiently to disengage its nose 11 from the horizontal reach 19 of the slide to permit the upward movement thereof and the disengagement of its stop-finger 28 from the verge-wheel 29.

When the movements, as previously enumerated, have been completed, the parts will have assumed the positions in which they are shown in Fig. 4. Now in the running of the clock and the continued rotation of the alarm-cam wheel 34, the same will snap forward under the urge of the spring 42, when the low-point of the slope 56 of the cam 36 has been brought into alignment with the alarm-cam finger 37. This forward movement of the alarm-cam wheel 34 and alarm-cam spring 42 will effect the retirement of the stop-finger 44 of the latter from the path of the hammer-tail 45 and thus permit the sounding of the alarm.

To stop the alarm in such manner that the same may be again automatically sounded twenty-four hours later, the user of the clock depresses the shut-off plunger 24, with the effect of similarly depressing the shut-off slide 20 against the counterurge of the spring 30, so as to engage the stop-finger 28 of the said slide with the teeth of the verge-wheel 29 to check the sounding of the alarm. During the downward movement of the slide 20 just described, the forward edge of the horizontal reach 19 thereof will have engaged the cam-surface 18 of the pivotal latch 10 and rocked the nose 18 thereof forward against the tension of the spring 53 until the said slide has reached its fully-depressed position, at which time the said nose will snap over the upper face of the said horizontal reach 19 and effectively retain the slide in its depressed alarm-shut-off position until such time during the running of the clock as the stop-finger 44 of the alarm-cam spring 42 has been moved into the path of the hammer-tail 45.

As before described, shortly after the stop-finger 44 has been interposed in the path of the hammer-tail 45, the pivotal latch 10 will have been rocked sufficiently by the inward movement of the alarm-cam wheel 34 to fully retire the nose 11 of the said latch and permit the slide to be moved into its upward or retired position by the spring 30, preparatory to another automatic release of the alarm.

In the event that the user of the clock wishes to cut the alarm out of action, a sliding alarm-stop 57 is provided which has sliding movement within the clock-case and 5 is provided with a finger 58 adapted to be moved into the path of the hammer-arm 48 by means of a finger-button 59 located upon the periphery of the case 26 and having a threaded stem 60 projecting inward, through

10 a slot 61 in the same and a slot 62 in the case-back 51, into engagement with a bushing 63 secured to the said shut-off slide 57.

By providing a pivotal latch, such as 10, for holding the alarm-shut-off slide or member 15 20 in its alarm-shut-off position, and operating the said lever by the alarm-cam 36, I am enabled to automatically release the said alarm-shut-off member for retirement, without imposing any appreciable retardation upon the time-train, so that the time-keeping properties thereof are not impaired.

I claim:

1. In an automatic alarm clock, the combination with the alarm-cam and alarm-control spring thereof; of a manually-operable alarm-shut-off member; spring-means normally urging the said shut-off member into its retired position; a pivotal latch physically distinct from the said alarm-control 30 spring for releasably holding the said alarm-shut-off member in its operative position and actuated by the said alarm-cam for releasing the said member for retirement by the said spring-means.

35 2. In an automatic alarm clock, the combination with the alarm-cam and alarm-control spring thereof; of a manually-operable alarm-shut-off member; spring-means normally urging the said shut-off member into 40 its retired position; a latch physically distinct from the said alarm-control spring and pivoted between its ends for releasably holding the said alarm-shut-off member in its operative position and having one end 45 provided with a latch-nose and its opposite end actuated by the said alarm-cam for releasing the said member for retirement by the said spring-means.

3. In an automatic alarm clock, the combination with the alarm-cam and alarm-control spring thereof; of a manually-operable reciprocating alarm-shut-off slide; spring-means normally urging the said slide into its retired position; a pivotal latch physically distinct from the said alarm-control 55 spring for releasably holding the said alarm-shut-off slide in its operative position and actuated by the said alarm-cam for releasing the said slide for retirement by the said 60 spring-means.

4. In an automatic alarm clock, the combination with the alarm-cam and alarm-control spring thereof; of a manually-operable reciprocating alarm-shut-off slide; spring- 65 means normally urging the said slide into

its retired position; a latch physically distinct from the said alarm-control spring and pivoted between its ends for releasably holding the said alarm-shut-off slide in its operative position and having one end provided with a latch-nose and its opposite end actuated by the said alarm-cam for releasing the said slide for retirement by the said spring-means.

5. In an automatic alarm clock, the combination with the alarm-set arbor, alarm-control spring and the alarm-cam thereof; of a manually-operable alarm-shut-off member; spring-means normally urging the said shut-off member into its retired position; a latch physically distinct from the said alarm-control spring and pivoted between its ends and having one end provided with a latch-nose for releasably holding the said alarm-shut-off member in its operative position and provided at its opposite end with a fork straddling the said alarm-set arbor in position to be moved by the said alarm-cam.

In testimony whereof, I have signed this specification.

ELOF L. CARLSON.
